US0D1079013S

(12) **United States Design Patent** (10) **Patent No.:** **US D1,079,013 S**
(45) **Date of Patent:** **** Jun. 10, 2025**

(54) **ORAL IRRIGATION DEVICE**

(71) Applicant: **Swiftsure Innovations Inc.**, Pasadena (CA)

(72) Inventors: **Deanne McCarthy**, Pasadena (CA); **Christopher Gillespie**, Toronto (CA); **Kathryn Atwell**, Halifax (CA); **Joel Ironstone**, Toronto (CA); **Matthew Asselin**, Toronto (CA); **Rory Tatchell**, Corner Brook (CA); **Angie Hughes**, Corner Brook (CA)

(73) Assignee: **Swiftsure Innovations Inc.** (CA)

(**) Term: **15 Years**

(21) Appl. No.: **29/812,329**

(22) Filed: **Oct. 20, 2021**

(51) LOC (15) Cl. **24-02**

(52) U.S. Cl.

USPC **D24/176; D24/110.5**

(58) **Field of Classification Search**

(57) **CLAIM**

The ornamental design for an oral irrigation device as shown and described.

DESCRIPTION

FIG. 1 is a perspective view of an oral irrigation device showing the new design;

FIG. 2 is a front view of the oral irrigation device of FIG. 1; FIG. 3 is a rear view of the oral irrigation device of FIG. 1; FIG. 4 is a top view of the oral irrigation device of FIG. 1; FIG. 5 is a bottom view of the oral irrigation device of FIG. 1;

FIG. 6 is a left side view of the oral irrigation device of FIG. 1; and,

FIG. 7 is a right side view of the oral irrigation device of FIG. 1.

The broken lines in the figures illustrate portions of the oral irrigation device that form no part of the claimed design.

1 Claim, 3 Drawing Sheets
